MOTOR FOR WINDSHIELD WIPERS

Filed Aug. 3, 1927

INVENTOR.
William M. Moxley
BY Shepherd & Campbell

ATTORNEY.

UNITED STATES PATENT OFFICE.

WILLIAM MILLER MOXLEY, OF MARCELINE, MISSOURI.

MOTOR FOR WINDSHIELD WIPERS.

Application filed August 3, 1927. Serial No. 210,310.

This invention relates to automatic windshield wipers, and it has for its object to provide an improved and simplified device of this character, adapted for use upon the windows of locomotive cabs, or upon the windshields of motor vehicles, and serving, when in place, to efficiently clear the glass of rain, snow, sleet and the like.

It is one of the important objects of the invention to provide a device of the character indicated, which will be simple in its nature, economical to construct, and very reliable in operation.

In the accompanying drawing, forming part of this application,

Fig. 1 is a central longitudinal sectional diagrammatic view, and

Fig. 2 is a transverse vertical sectional view taken on the line of the bearing brackets of the transverse shaft of the pinion, herein-after described.

Like numerals designate corresponding parts in both of the figures of the drawing.

Referring to the drawing, 5 designates a cylinder in which two pistons 6 are mounted to slide. A piston rod 7 connects the pistons 6, and is provided, upon one of its sides, with a rack 8, which meshes with a toothed pinion 9. An arm 10 projects from the pinion 9, and at its extremity has pivotal engagement with a wiper 11, adapted to be moved back and forth over the face of the glass to be cleared, as the pistons 6 reciprocate in the cylinder 5. The cylinder heads 12-12^a carry valve casings 13-13^a. These casings comprise cylinders 14-14^a in which pistons 15-15^a are located. Rods 16-16^a which are carried by said pistons constitute the stems of exhaust valves 17-17^a, and air control valves 18-18^a. A main air supply line 19, having a control valve 20, in its length, connects through branches 21 and 22, with ports 23-23^a of the respective valve casings. A conduit 24 connects at its left hand end with the left hand end of the cylinder 5, and at its right hand end with the cylinder 14^a. A conduit 25 connects, at its left hand end, with the cylinder 14 and at its right hand end with the right hand end of the cylinder 5.

With the parts in the position illustrated in the drawing, air is being admitted through conduits 19 and 21 to the left hand end of the cylinder, the air valve 18 being unseated and air valve 18^a being closed. At this time the right hand end of the cylinder is in communication with the atmosphere through an ex-

haust port 27^a. Consequently, the piston 6 and piston rod 7 will be moved toward the right, and in so doing will impart a stroke to the wiper 11. When the pistons have nearly reached their limit of movement toward the right, the right hand end of the piston rod 7 will abut against the stem of the valve 18^a, and will move said valve, and the exhaust valve, and the piston 15^a toward the right. This will unseat the air valve 18^a, and will close the exhaust port 27^a. The entry of the air to the right hand end of the cylinder will tend to move the pistons toward the left, and as soon as any pressure accumulates in the cylinder, said pressure will find its way by the conduit 25 to the left hand end of the cylinder 14, where it will act upon the piston 15 to move said piston and its associated valve toward the right, thereby seating the air valve 18, and unseating the exhaust valve 17. The unseating of the exhaust valve will bring the left hand end of the cylinder into communication with the atmosphere through exhaust port 27, and the result will be that the pistons will travel toward the left, imparting a stroke to the wiper 11 in the opposite direction. It is clear that when the pistons reach their limit of movement toward the left, the piston rod 7 will strike the stem of the valve 18, and restore it to the position illustrated in Fig. 1, thereby admitting pressure fluid to the left hand end of the cylinder. This pressure fluid will find its way by conduit 24, to the right hand end of cylinder 14, moving piston 15^a to the left, to seat air valve 18^a and unseat exhaust valve 17^a.

The pinion 9 is mounted upon a transverse shaft 9^a, that is supported upon inwardly projecting brackets 28, and the ends of this shaft project to the exterior of the cylinder, and one end of the shaft is preferably provided with a crank 29, by which an initial movement may be imparted to the mechanism, manually, if the mechanism should become stuck for any reason, as, for example, when it has not been used for some time.

By providing two pistons, and by disposing the rack and pinion between these two pistons, I avoid the necessity of packing piston rods or of providing a fluid tight joint about the part where the arm 10 passes from the interior of the cylinder to the exterior thereof.

The mechanism herein shown and described is of extreme simplicity, may be

made of a rugged construction, and will last for a very long time with a minimum of attention.

It is to be understood that the invention is not limited to the precise construction set forth, but that it includes within its purview whatever changes fairly come either within the terms or the spirit of the appended claims.

10 Having described my invention, what I claim is:

1. In a windshield wiper motor, a cylinder, a piston therein, a rack bar operated by the piston, a pinion which meshes with said rack bar, opposed valve casings for controlling the flow of fluid pressure to the opposite ends of said cylinder, opposed valves each comprising inlet and exhaust valves therein, pistons for operating said valves, and means 20 for moving said valves in one direction under the direct action of the piston in the cylinder, and in the other direction under fluid pressure.

2. A device of the character described, comprising a cylinder, a pair of pistons therein, a rack between the pistons, a pinion engaged with said rack, a pair of valve casings, one at each end of the cylinder, each of said valve casings comprising a cylinder and a valve piston therein, an exhaust valve and an air valve carried by each of the valve pistons, a conduit leading from each of the valve cylinders to and communicating with the remote end of the cylinder, said valves being

disposed in the line of travel of the pistons 35 and being arranged to be contacted with, and moved outwardly by the direct action of said pistons, and exhaust ports controlled by said exhaust valves, and serving when uncovered by said valves to establish communication between the interior of the cylinder and the atmosphere, said conduit serving, when air pressure is created in the remote end of the cylinder to conduct such air pressure to the valve casing where it acts 45 upon the valve piston to shift the same to close the air valve and open the exhaust valve.

3. A device of the character described, comprising a cylinder, a pair of pistons 50 therein, a rack bar between said pistons, a pinion with which said rack bar meshes, a transverse shaft by which said pinion is carried, which shaft projects to the exterior of the cylinder, a pressure fluid supply line, a 55 valve at each end of the cylinder for controlling the fluid pressure thereto, and for controlling the exhaust fluid therefrom, means for shifting said valves outwardly under the direct action of the pistons at their 60 respective limits of travel, and for shifting said valves in the other direction, under the action of the fluid pressure taken from the end of the cylinder remote from the valve being moved.

65 In testimony whereof I affix my signature.

WILLIAM MILLER MOXLEY.
